Primary Examiner — George D. Kirschbaum*Assistant Examiner* — Clese Moore, Jr.(74) Attorney, Agent, or Firm — Celina M. Orr; Carstens & Cahoon, LLP(57) CLAIM

The ornamental design for a swaddle, as shown and described.

DESCRIPTION

FIG. 1 is a perspective view of a swaddle, showing my new design, being worn;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing a human head in FIG. 1 illustrate environmental matter and form no part of the claimed design.
